UNITED STATES PATENT OFFICE.

CAMILLE LOUIS MARIE RAVUT, OF PARIS, FRANCE, ASSIGNOR TO SOCIÉTÉ INDUSTRIELLE DES TÉLÉPHONES (CONSTRUCTIONS ÉLECTRIQUES, CAOUTCHOUC, CÂBLES), OF PARIS, FRANCE.

ELECTRIC CONNECTION.

Application filed July 8, 1924, Serial No. 724,870, and in France February 28, 1924.

The present invention relates to a system of electric connections, chiefly applicable to long-distance telephony, in which the wires are used to a better advantage than in the known system employing pairs of wires or double pairs in combination. The principle of the invention consists in disposing the wires in groups of three, or in forming three-wire sets instead of pairs of wires, and three triple wires instead of two double wires. With each three-wire set, by reason of suitable separating arrangements at the ends of the line, we are enabled to provide two independent effective circuits for telephone or like communication, and with the use of a triple three-wire circuit we are enabled to provide a combination or phantom three-wire circuit comprising two additional communication circuits which are independent of each other and independent of the communication circuits offered by each of the component three-wire physical circuits. In this manner, the wires are more efficiently employed than in the known system. Taking as an example a group of 72 conductors—to facilitate the calculations—if the conductors are disposed in double pairs they will constitute 18 double pairs and will hence afford 36 physical communication circuits of the usual type or of the first class; as well as 18 phantom communication circuits, or circuits of the second class. But if the said conductors are disposed as triple three-wire circuits, they will form 8 triple three-wire circuits, i. e. $3 \times 8 = 24$ physical three-wire circuits providing $2 \times 24 = 48$ communication lines of the first class, while the phantom circuits will afford $2 \times 8 = 16$ communication circuits of the second class. By my arrangement of the conductors in triple three-wire sets, we are thus enabled to provide $48 - 36 = 12$ effective circuits of the first class in addition to what is obtained with the double pair grouping, while on the other hand the second class circuits will be diminished by $18 - 16 = 2$ circuits. However the total gain will be $(48 + 16) - (36 + 18) = 10$ effective circuits, so that the efficiency of the set of 72 conductors is aug-

mented by about 20 per cent by my said arrangement. 50

The characteristics of the telephone communications of the first class are identical—within the limits of uniformity of the electric constants of the several conductors of the set—but differ from the characteristics of the conductors of the second class. 55

The following description, together with the appended drawings which are given by way of example, sets forth my said invention. 60

Figs. 1 and 2 show respectively in cross section and in elevation the three conductors forming a three-wire set. 65

Fig. 3 represents a line circuit.

Fig. 4 is a diagram of a complete installation.

Fig. 5 is a diagram of the arrangement of circuits at the ends of the line.

Fig. 6 shows a line employing a triple three-wire set. 70

In the system according to the present invention, the wires are disposed in three-wire sets and in triple three-wire sets. It is understood that the three wires of a set have an identical construction and insulation, and they are moreover formed into a cable strand of the three-wire type, the three insulated conductors being juxtaposed and twisted in helical form around a common geometric axis, in such manner that the centres of the three conductors upon a plane perpendicular to the cable axis shall represent the three vertices of an equilateral triangle, Figs. 1 and 2. When this arrangement is to be tripled, each of the constituent three-wire sets is considered as a single conductor, and the preceding remarks will be equally applicable. By the use of adequate arrangements at the ends of the line, in accordance with certain conditions to be hereinafter set forth, the independent circuits can be properly separated. 75 80 85

The present invention, although chiefly applicable to telephone cables, is independent of the nature of the conductors and the insulation, and relates to sets of overhead line wires as well as to conductors in the 90 95

form of cables, and the conditions can be transposed in an immediate manner.

Considering in the first place a single set of three conductors, the three wires are identical and are geometrically situated in conditions of symmetry such that their relative position in pairs is always the same.

Let R be the resistance of each wire per unit length.

L the coefficient of self-induction of each wire per unit length.

C_0 the capacity of each wire per unit length relative to the sheathing.

M the coefficient of mutual induction of any two wires of the set, per unit length.

C the capacity of any two wires relative to each other, per unit of length.

G_0 and G the losses per unit length re-

spectively between a wire and the set, and between one wire and another, per unit length.

v^1, v^2, v^3 the potential of each wire at the distance x from the initial or zero point.

i^1, i^2, i^3 the current in each wire at the distance x from the zero point.

For the distance x from the zero point, the equations of propagation will be:

$$(1) \begin{cases} -\frac{\delta v_1}{\delta x} = \left(R + L \frac{\delta}{\delta t} \right) i_1 + M \frac{\delta}{\delta t} i_2 + M \frac{\delta}{\delta t} i_3 \\ -\frac{\delta v_2}{\delta x} = M \frac{\delta}{\delta t} i_1 + \left(R + L \frac{\delta}{\delta t} \right) i_2 + M \frac{\delta}{\delta t} i_3 \\ -\frac{\delta v_3}{\delta x} = M \frac{\delta}{\delta t} i_1 + M \frac{\delta}{\delta t} i_2 + \left(R + L \frac{\delta}{\delta t} \right) i_3 \end{cases} \quad 30$$

$$(2) \begin{cases} -\frac{\delta i_1}{\delta x} = \left[(G_0 + 2G) + (C_0 + 2C) \frac{\delta}{\delta t} \right] v_1 - \left(G + C \frac{\delta}{\delta t} \right) v_2 - \left(G + C \frac{\delta}{\delta t} \right) v_3 \\ -\frac{\delta i_2}{\delta x} = -\left(G + C \frac{\delta}{\delta t} \right) v_1 + \left[(G_0 + 2G) + (C_0 + 2C) \frac{\delta}{\delta t} \right] v_2 - \left(G + C \frac{\delta}{\delta t} \right) v_3 \\ -\frac{\delta i_3}{\delta x} = -\left(G + C \frac{\delta}{\delta t} \right) v_1 - \left(G + C \frac{\delta}{\delta t} \right) v_2 + \left[(G_0 + 2G) + (C_0 + 2C) \frac{\delta}{\delta t} \right] v_3 \end{cases}$$

If we designate by α and α^2 the two imaginary cube roots of unity, and by $\lambda_1 = \lambda$; $\lambda_2 = p \cdot \lambda$; $\mu_1 = \mu$; $\mu_2 = q \cdot \mu$; four numerical coefficients which can be temporarily given any desired value, and are subjected solely to the condition $\lambda_1 \mu_2 - \lambda_2 \mu_1 \neq 0$, or what is the same, $(3) p - q \neq 0$ we can at once substitute for the six equations (1) and (2) the three pairs of equations:

$$(6) \begin{cases} -\frac{\delta}{\delta x} (v_1 + v_2 + v_3) = \left\{ R + (L + 2M) \frac{\delta}{\delta t} \right\} (i_1 + i_2 + i_3) \\ -\frac{\delta}{\delta x} (i_1 + i_2 + i_3) = \left\{ G_0 + C_0 \frac{\delta}{\delta t} \right\} (v_1 + v_2 + v_3) \end{cases}$$

$v_\lambda, i_\lambda, v_\mu, i_\mu$ being defined by the equations

$$(7) \begin{cases} v_\lambda = \lambda \{ (v_1 + \alpha v_2 + \alpha^2 v_3) + p (v_1 + \alpha^2 v_2 + \alpha v_3) \} \\ i_\lambda = \lambda \{ (i_1 + \alpha i_2 + \alpha^2 i_3) + p (i_1 + \alpha^2 i_2 + \alpha i_3) \} \\ v_\mu = \mu \{ (v_1 + \alpha v_2 + \alpha^2 v_3) + q (v_1 + \alpha^2 v_2 + \alpha v_3) \} \\ i_\mu = \mu \{ (i_1 + \alpha i_2 + \alpha^2 i_3) + q (i_1 + \alpha^2 i_2 + \alpha i_3) \} \end{cases}$$

The equations (4) characterize the propagation of the potential v_λ and the current $\frac{1}{2} i_\lambda$ along a line consisting of two wires of the three-wire set in series, the third wire being separate. The equations (5) characterize the propagation of the potential v_μ and the current $\frac{1}{2} i_\mu$ along an identical line. These

two propagations are of the first class. The equations (6) characterize the propagation of the potential $\frac{1}{3} (v_1 + v_2 + v_3)$ and the current $(i_1 + i_2 + i_3)$ along the three wires of the set connected in parallel, adjacent the earth.

The equivalence of the equations (1) and (2) on the one hand and of the three pairs of equations (4) (5) (6) on the other hand, shows that the real propagation of potentials and currents $v_1, v_2, v_3; i_1, i_2, i_3$ in the three wires of the set is equivalent to the superposition of three virtual propagations of an independent nature which have been above specified.

Since the imaginary cube roots of unity have introduced the symbol $\sqrt{-1}$, it will be henceforth supposed that the considerations will bear upon potentials and currents which are functions of the time and have the form $A \cdot e^{i\omega t}$, it being understood that finally, by retaining only the real portions, for instance,

and not departing from linear relations between potentials and currents, the results can be transposed into the domain of sinusoidal currents.

In this condition, it is feasible to employ terminal arrangements, Fig. 4, which are connected by three terminals $B_1 B_2 B_3$ to the three wires of the set, by two pairs of terminals $A_1 A'_1 A_2 A'_2$ to two independent sources of current, and by the last terminal A_0 to a third source of current whose other pole is grounded; this disposition has the following particular features:

1. The source of current connected at $A_1 A'_1$ only intervenes in the value of the line potentials and currents by modifying the value of the potential v_λ and the current i_λ .

2. The source of current connected at $A_2 A'_2$ acts only upon the combinations v_μ and i_μ of the line potentials and currents.

3. The source of current connected at A_0 acts only upon the combinations $v_1 + v_2 + v_3$ and $i_1 + i_2 + i_3$.

Since the nature of $v_\lambda, i_\lambda, v_\mu, i_\mu$ will depend upon the arbitrary values λ, μ, p, q , a great variety of dispositions can be employed, according to the values which are selected for these four factors, it being however stipulated that p must be other than q . It can be readily demonstrated that $p + q$ should have a zero-value. We may likewise determine the conditions to be complied with by an arrangement comprising three outgoing terminals $B_1 B_2 B_3$ and two pairs of incoming terminals $A_1 A'_1, A_2 A'_2$ with an additional incoming terminal A_0 , in order to possess the above mentioned properties. We will indicate the required conditions and show how these are obtained. In this case it is understood that if a disposition comprising the above-mentioned incoming and outgoing terminals complies with the conditions to be hereinafter set forth—which can be shown by experiment—the values $\lambda \mu p q$ (real or imaginary) will exist, by means of which we may set out potentials and currents $v_\lambda i_\lambda v_\mu i_\mu$ in accordance with the formulæ (7), in such manner that the action will take place as if the source of current connected at $A_1 A'_1$ acted directly upon the

potential v_λ and the current $\frac{1}{2} i_\lambda$, the source connected at $A_2 A'_2$ upon the potential v_μ and the current $\frac{1}{2} i_\mu$, and the source con-

nected at A_0 upon the potential $\frac{v_1 + v_2 + v_3}{3}$ and the current $i_1 + i_2 + i_3$.

If we connect two identical arrangements to the two ends of the line (Fig. 4), the source of current $A_1 A'_1$ will act only upon $v_\lambda i_\lambda$ which will be propagated along the three-wire set as if these were alone preva-

lent, and will act at the receiving end upon $C_1 C'_1$ for instance, as if the other receivers did not exist. A like action will take place between $A_2 A'_2$ and $C_2 C'_2$ and between A_0 and C_0 . We thus obtain on the three-wire set three entirely separate communications.

Since the potentials and currents $v_\lambda, \frac{1}{2} i_\lambda$ or $v_\mu, \frac{1}{2} i_\mu$ are each propagated along a line similar to what would be constituted by two wires of the three-wire set—the third wire being isolated—it will be observed that whatever may be the values of $\lambda \mu p q$, the sole fact that the terminal circuits comply with the conditions to be hereinafter set forth implies the obtainment of three independent communications.

We will briefly indicate the method of attaining the condition $p + q = 0$, and the conditions stipulated for the terminal circuits.

Let $v_1 v_2 v_3$ (Fig. 4) be the potentials of the three terminals $B_1 B_2 B_3$; $u_1 u_2$ the potential differences applied between the terminals A_1 and A'_1 and between the terminals $A_2 A'_2$; and u_0 the potential applied to the terminal A_0 ; $j_1 j_2 j_3$ are the currents from the terminal arrangement which maintain the various potentials.

We will take as a starting point the general theory indicated by M. C. Ravut in the "Revue Générale de l'Electricité," vol. XIV, No. 17. This theory shows that in a circulation network having s poles or terminals connected by connecting currents with outside sources of supply, if the said poles constitute n groups in such manner that in each group the connecting currents have a simple relation such as a linear relation, there will exist a function, quadratic, homogeneous and of the second degree, H , of the connecting currents of the other $s - n$ poles, such that the half-derivative of this function H relative to one of these $s - n$ connecting currents shall be equal to the difference of potential between the corresponding pole and a reference pole chosen from each of the n groups.

The terminal disposition here considered is in fact a network having 8 terminals distributed in three groups.

1. The group $B_1 B_2 B_3$ whereof the reference pole is the pole A_0 , the currents being $i_1 i_2 i_3$ and j_0 , in such manner that $i_1 + i_2 + i_3 + j_0 = 0$.

2. The group $A_1 A'_1$, one of these two poles being a reference pole, the currents being j_1 and $-j_1$ in such manner that $j_1 + (-j_1) = 0$.

3. The group $A_2 A'_2$, one of these two poles being a reference pole, the currents being j_2 and $-j_2$ in such manner that $j_2 + (-j_2) = 0$.

The characteristic function is in this case

a quadratic function of five currents $i_1 i_2 i_3 i_1 j_2$, for instance.

$$5 (8) \quad \left\{ \begin{array}{l} H = a_1^1 i_1^2 + a_2^2 i_2^2 + a_3^3 i_3^2 \\ \quad + 2a_1^2 i_1 i_2 + 2a_2^2 i_2 i_3 + 2a_3^2 i_3 i_1 \\ \quad + b_1^1 j_1^2 + b_2^2 j_2^2 + 2b_1^2 j_1 j_2 + 2c_1 j_1 i_1 + 2c_2 j_1 i_2 \\ \quad + 2c_3 j_1 i_3 + 2d_1 j_2 i_1 + 2d_2 j_2 i_2 + 2d_3 j_2 i_3 \end{array} \right.$$

whence

$$10 (9) \quad \left\{ \begin{array}{l} v_1 - u_0 = \frac{1}{2} \frac{\delta H}{\delta i_1} \quad u_1 = \frac{1}{2} \frac{\delta H}{\delta j_1} \\ v_2 - u_0 = \frac{1}{2} \frac{\delta H}{\delta i_2} \quad u_2 = \frac{1}{2} \frac{\delta H}{\delta j_2} \\ v_3 - u_0 = \frac{1}{2} \frac{\delta H}{\delta i_3} \quad u_3 = \frac{1}{2} \frac{\delta H}{\delta j_3} \end{array} \right.$$

15 The equation

$$v_1 + \alpha v_2 + \alpha^2 v_3 \equiv (v_1 - u_0) + \alpha(v_2 - u_0) + \alpha^2(v_3 - u_0)$$

$$10 (10) \quad \left\{ \begin{array}{l} c_1 + c_2 + c_3 = 0; \quad d_1 + d_2 + d_3 = 0; \\ c_1 d_1 + c_2 d_2 + c_3 d_3 = 0; \quad a_1^1 - a_2^3 = a_2^2 - a_3^1 = a_3^3 - a_1^2; \\ \frac{a_1^3 - a_2^1}{c_1 d_1} = \frac{a_2^1 - a_3^2}{c_2 d_2} = \frac{a_3^2 - a_1^3}{c_3 d_3}; \quad b_1^2 = 0; \end{array} \right.$$

35 and we also find

$$11 (11) \quad p = -q = \frac{c_1 + \alpha c_2 + \alpha^2 c_3}{c_1 + \alpha^2 c_2 + \alpha c_3} = -\frac{d_1 + \alpha d_2 + \alpha^2 d_3}{d_1 + \alpha^2 d_2 + \alpha d_3}$$

whence: $p + q = 0$, these latter equations being compatible with the equations (10).

If a given arrangement complies with the conditions (10) we find for $v_\lambda i_\lambda v_\mu i_\mu$ the values

$$45 (12) \quad \left\{ \begin{array}{l} v_\lambda = \lambda^1 (c_1 v_1 + c_2 v_2 + c_3 v_3) \\ v_\lambda = \lambda^1 (c_1 i_1 + c_2 i_2 + c_3 i_3) \\ v_\mu = \mu^1 (d_1 v_1 + d_2 v_2 + d_3 v_3) \\ v_\mu = \mu^1 (d_1 i_1 + d_2 i_2 + d_3 i_3) \end{array} \right.$$

λ^1 and μ^1 being coefficients of proportionality which are not defined, the c and the d being the coefficients of the characteristic H of the arrangement.

By reason of the first conditions (10), $v_\lambda i_\lambda v_\mu i_\mu$ will in fact have the form indicated in the equations (7), and the problem is solved wherein we act individually by the s sources upon potentials and currents propagated over the three-wire set according to the equations (4) (5) and (6).

60 The coefficients a, b, c, d of the function H (which are homogeneous with impedances) may be calculated according to the diagram of circuits; they may also be measured upon an arrangement which is constituted in order to ascertain whether the conditions (10) have been properly carried out.

We may provide a physical expression of the conditions (10) by returning to the equations (9). We can readily verify whether these conditions (10) are equivalent to the following:

70 1. Condition $b_1^2 = 0$.—The two outer circuits $A_1 A'_1$ and $A_2 A'_2$ should be independent of each other after the manner of the two diagonals of a balanced Wheatstone bridge, when the outer terminals $B_1 B_2 B_3$ are isolated.

permits the formation of the linear functions

(7) $v_\lambda i_\lambda v_\mu i_\mu$ depending upon the second members of the first three equations (9).

We then substitute in the first three equations (9) the expressions of v_λ , of v_μ and of the combination $v_1 + v_2 + v_3 - 3u_0$; we then stipulate that v_λ and u_1 depend only upon the combination i_λ of the i, j_1 and that v_μ and u_2 depend only upon the combination i_μ of the i and of the j_2 ; also $v_1 + v_2 + v_3 - 3u_0$ depends only upon $i_1 + i_2 + i_3$ which is equal to j_0 .

By rearranging the conditions thus obtained, we can readily find the following equations:

2. Conditions $c_1 + c_2 + c_3 = 0$ and $d_1 + d_2 + d_3 = 0$.—If a potential difference u is used between the terminals $A_1 A'_1$, the sum of the potential differences between each outer terminal $B_1 B_2 B_3$ and the supplementary terminal A_0 should be null, and irrespectively of the value of the external impedance inserted between the terminals A_2 and A'_2 . The same is true if in the preceding case we use $A_2 A'_2$ instead of $A_1 A'_1$ or $A_1' A'_1$ instead of $A_2 A'_2$.

3. Conditions $a_1^1 - a_2^3 = a_2^2 - a_3^1 = a_3^3 - a_1^2$.—If we isolate the four terminals $A_1 A'_1 A_2 A'_2$ and use between each terminal $B_1 B_2 B_3$ and the terminal A_0 potential differences whose sum is zero (e. g. three potential differences on the three-phase system) the current traversing the supplementary terminal A_0 should be null.

4. Conditions $\frac{a_1^3 - a_2^1}{c_1 d_1} = \frac{a_2^1 - a_3^2}{c_2 d_2} = \frac{a_3^2 - a_1^3}{c_3 d_3}$.

Since the terminals $A_1 A'_1 A_2 A'_2$ and $B_2 B_3$ are isolated a current i is caused to enter at the terminal B_1 and to leave at the terminal A_1 .

It produces between A_1 and A'_1 a potential difference u_1 , between A_2 and A'_2 a potential difference u_2 , and between B_2 and B_3 a potential difference $v_2 - v_3$. We determine the fourth proportional factor ϕ for these three potential differences. If we now treat the three terminals $B_1 B_2 B_3$ by circular permutation, while maintaining a constant value for the current i , this fourth factor should remain constant in the three measurements. In this case as well as in the rest of my exposition, the potentials are considered in the vector form $v = V e^{j\delta}$, δ being the phase of v with respect to an initial point which is of an arbitrary nature.

5. Condition $c_1 d_1 + c_2 d_2 + c_3 d_3 = 0$.—This condition is satisfied when the conditions specified in the preceding paragraph are

satisfied. The independence of the communications exchanged between $A_1 A'_1$ and $C_1 C'_1$ on the other hand, between $A_2 A'_2$ and $C_2 C'_2$ on the other hand, and further, between A_0 and C_0 , will prevail irrespectively of the variations in the a 's, b 's, c 's and d 's relative to the pulsation, at least for all pulsations for which the conditions (10) are complied with; but in this case the potentials and currents v_λ i_λ and v_μ i_μ which are propagated individually over the three-wire set are differently compounded, according to the frequencies, with the potentials and currents of the three wires of the set. For this reason one of the communications will be entirely confused and unintelligible upon the whole length of the line connecting the end outfits, although it will be very clear and without confusion between the corresponding outfits. The whole action will take place as if the various pulsations concerned in the telephone communication became separated in the connecting arrangement at the transmitting end and were separately distributed, each in its own manner, upon the three wires of the set between the outfits at each end, then coming together in an accurate manner in the connecting arrangement at the receiving end—except for any distortion which may be due to the length of the three-wire line.

As an example of a practical connecting arrangement, we will describe the arrangement which is illustrated in Fig. 5. T_1 is a transformer in which the middle part of the secondary is accessible, this being analogous to a coil of the telegraphic type which is in current use for two-wire telephone circuits; T_2 is a transformer of the usual type with two windings. $T_3 T'_3 T''_3$ are three similar transformers each of which is provided with two windings.

The primary windings of the transformers $T_3 T'_3 T''_3$ are disposed on the star system about a central point which is connected to the external incoming terminal A_0 . The said primary windings are each connected to one

of the three outgoing terminals $B_1 B_2 B_3$ to which are connected the ends of the three wires of the telephone line.

The secondary windings of the transformers $T_3 T'_3 T''_3$ are also disposed on the star system about an isolated central point. Further, the secondaries Nos. 1 and 2, corresponding to the outgoing terminals B_1 and B_2 , are each connected to one end of the secondary of the transformer T_1 . The middle point of the secondary of T_1 is connected to the outgoing end of the secondary No. 3 of the group $T_3 T'_3 T''_3$ —corresponding to the terminal B_3 —through the secondary of the transformer T_2 . The primary of T_1 is connected to the two incoming terminals $A_1 A'_1$ and the primary of T_2 to the two incoming terminals $A_2 A'_2$. The sources of current are disposed as follows: (1) between A_1 and A'_1 , (2) between A_2 and A'_2 , (3) between A_0 and ground.

The following designations are employed: Z_1 the impedance of the primary circuit of T_1 .

Z'_1 the total impedance of the secondary of T_1 .

ZM_1 the mutual induction between the primary of T_1 and the entire secondary.

M'_1 the mutual induction between the two halves of the secondary of T_1 .

Z_2 the impedance of the primary of T_2 .

Z'_2 the impedance of the secondary of T_2 .

M_2 the mutual induction between the two windings of T_2 .

Z_3 the impedance of the primary of T_3 , T'_3 or T''_3 .

Z'_3 the impedance of the secondary of T_3 , T'_3 or T''_3 .

M_3 the mutual induction between the two windings of T_3 , T'_3 or T''_3 .

If we employ Kirchoff's equations for this system, and if we seek for the coefficients a b c d of the characteristic function H , we will find the following equations by an easy calculation.

$$(13) \quad \left\{ \begin{array}{l} a_2^1 = a_1^1 = Z_3 + \frac{\omega^2 M_3^2}{2} \left(\frac{1}{A} + \frac{1}{B} \right); \quad a_1^3 = a_2^3 = -\frac{\omega^2 M_3^2}{B}; \\ a_1^1 + a_1^2 = a_3^3 + a_2^3 + \frac{\omega^2 M_3^2}{B}; \quad b_1^2 = 0; \\ c_1 = -c_2 = -\frac{\omega^2 M_1 M_3}{A}; \quad c_3 = 0; \\ d_1 = d_2 = -\frac{1}{2} d_3 = -\frac{\omega^2 M_2 M_3}{B}. \end{array} \right.$$

When:

$$A = Z_1' + Z_3' + j\omega M_1'; \quad B = Z_1' + 2Z_3' + 3Z_3' - j\omega M_1'.$$

The arrangement thus verifies the conditions (10). In this particular case, v_λ and v_μ assume the simple forms

$$(14) \quad \left\{ \begin{array}{l} v_\lambda = \lambda' (v_1 - v_2) \quad i_\lambda = \lambda' (i_1 - i_2) \\ v_\mu = \mu' (v_1 + v_2 + v_3) \quad i_\mu = \mu' (i_1 + i_2 + i_3) \end{array} \right.$$

so that the compounding of v_λ and v_μ with $v_1 v_2 v_3$ will not vary with the pulsation.

The said arrangement verifies the conditions (10) irrespectively of the pulsation.

ω , and it can thus be employed both for telephony and telegraphy.

The preceding considerations will now be applied to the case of a triple three-wire line.

1. We made use of three triple circuits of the type which has been above considered, these resembling each other as closely as possible.

10 2. The three triple circuits are also wound together in a cable, each being treated as a separate conductor of a three-wire circuit.

In these conditions we may make the following suppositions:

15 1. The resistance per unit length of any one of the nine wires of the three triple circuits is the same, this being represented by R .

20 2. The self-induction of each wire per unit length is also the same, this being represented by L .

3. The mutual induction of the wires of any given three-wire set, taken in pairs, is the same (represented by M) irrespectively 25 of the three-wire set containing the same.

4. The mutual induction of any two wires, one pertaining to a given three-wire set and the second to another three-wire set, is the same (M_1).

30 5. The capacity of a pair of wires of a given three-wire set is the same (C) irrespectively of the three-wire set containing the said wires; the same is true for the conductance representing the losses (G).

35 6. The capacity of a pair of wires whereof one pertains to a given three-wire set and the second to another three-wire set is the same (C'); the same is true for the value of the loss (G').

40 7. The three triple circuits are supposed to be sufficiently symmetrical in order that the capacity C_0 and the loss G_0 relative to the sheathing of the cable shall be the same for all the wires.

45 In these conditions, we will constitute for each wire the equations showing the relation between the fall of potential along a given element of the length and the effect of the ohmic resistance as well as the electro-motive forces of induction, and in like manner for each wire, the equation evaluating the leakage current which leaves the conductors at each point, taking due account of the capacities and losses as well as the distribution of

50 potential in the plane perpendicular to the centre line of the three triple circuits. We will specify for each three-wire set the above-mentioned potentials and currents $v_\lambda i_\lambda v_\mu i_\mu$; in this case, the values of $v_\lambda i_\lambda$ and relative

55 to a three-wire circuit comprise only the currents pertaining to this same circuit, so that all that has been stated for one three-wire set concerning the propagations of $v_\lambda i_\lambda$ and of $v_\mu i_\mu$ will hold good. We will further 60 specify $v_1 + v_2 + v_3$ for each three-wire set,

and it is found that the equations giving $(v_1 + v_2 + v_3)$ for the three triple circuits do not contain the currents of the nine wires in question, except by the combination $i_1 + i_2 + i_3$ employed for each three-wire set. We thus postulate $v_1 + v_2 + v_3 = v'_1$ for the first three-wire set, v'_2 for the second set, and v'_3 for the third set. In like manner, we have $i_1 + i_2 + i_3 = i'_1$ or i'_2 , or i'_3 for the three sets respectively; between the values of v' and i' , the equations have exactly the same form as the initial equations (1), and only the values of the coefficients have changed.

70 For this reason we may consider the three additional incoming poles $A_1^1 A_2^1 A_3^1$ of the arrangements serving to connect each three-wire set of the triple combination as forming the end of one of the wires of the phantom three-wire circuit. In like manner at the other end, as concerns the additional outgoing poles $C_1^1 C_2^1 C_3^1$, the same conditions prevail. So that all that has been specified for the three-wire circuit alone will now prevail for the phantom three-wire circuit, and the conditions (10) will apply to the end connecting arrangements for the phantom three-wire circuit. But the optimum specification, i. e. the conditions to be complied with by the constants of the line will not be the same for the end connecting arrangements 85 pertaining to the phantom three-wire set as for the arrangements used with the physical three-wire sets.

90 With reference to the above-mentioned form of construction, Fig. 6 shows the end connecting arrangements for a triple three-wire set whose phantom three-wire circuit is utilized. The independent communications are as follows:

100 First three-wire set:
 $A_1^1 A_2^1 A_3^1$ with $C_1^1 C_2^1 C_3^1$

Second three-wire set:
 $A_1^2 A_2^2 A_3^2$ with $C_1^2 C_2^2 C_3^2$

110 Third three-wire set:
 $A_1^3 A_2^3 A_3^3$ with $C_1^3 C_2^3 C_3^3$

Phantom circuits:
 $A_1^t A_2^t A_3^t$ with $C_1^t C_2^t C_3^t$

115 There will also be an independent communication between A_1^t and C_1^t , relating to the potentials and currents $\Sigma(v)$ and $\Sigma(i)$ on the nine wires of the triple three-wire combination. This is the transposition of 120 the telegraphic method for phantom circuits in double pairs.

If the self induction of the various communication circuits is insufficient and if it is desired to employ the Pupin method for a 125 triple three-wire circuit, it is advisable to employ one Pupin coil for each wire; this arrangement is the only one by which we may take account of the distribution of the potential in each wire in the specification of 130

the values of v_λ and v_μ , and of the distribution of the current in each wire for the values of i_λ and i_μ . The coils for each three-wire set, and even of an entire triple three-wire combination should be balanced to the maximum degree.

Each telephone communication circuit can be used with suitable amplifying relays, in the same manner as for known circuits, but 10 it is necessary to employ various connecting arrangements in the relay installation whereby the independent communications can be separated from each other.

What I claim is:—

- 15 1. A system of long distance telephonic or other electric communication comprising three insulated wires having an identical construction and insulation, juxtaposed and twisted in helical form around a common 20 geometric axis, in such manner that the centers of the three conductors upon a plane perpendicular to the twisting axis occupy the three vertices of an equilateral triangle, thus forming what is called a three-wire set, 25 another three-wire set analogous to the first one, a third three-wire set analogous to the others, the common winding of the three three-wire sets being juxtaposed and twisted in helical form around a common geometric 30 axis in such manner that the traces of the axes of the three three-wire sets upon a plane perpendicular to the common twisting axis occupy the three vertices of an equilateral triangle, three transformers at each end of 35 each three-wire set, two independent sources of current, a transformer connected to the two poles of the first independent source of current, the primaries of the three first transformers being connected respectively 40 with the wires of the three-wire set and disposed on the star system about a central point connected to a special wire, the secondaries of the three first transformers being disposed on the star system about an insulated point, said secondaries being connected respectively with the ends and the middle point of the secondary of the fourth transformer and the series intercalation of the secondary of the second independent 45 source upon the connecting wire ending at the middle point of the transformer which is connected to the two terminals of the first independent source of current, the application to the three special wires provided each 50 in a three-wire set of a terminal arrangement similar to those applied to each three-wire set.
2. A system of electrical communication such as a long distance telephone system comprising the following instrumentalities: 60 three conducting units or sets of three wires each twisted in a helical form around a common geometric axis, so that the centers of the three conductors in each set in any plane perpendicular to the common axis are at the vertices of an equi-lateral triangle, all of the three unit sets being likewise twisted around a common geometric axis so that in any planes perpendicular to said axis the geometric centers of the three several units 65 will also form an equi-lateral triangle; three transformers at each end of each three-wire set or unit, and two independent signaling circuits; one terminal of the primary of each of said transformers being connected to one of the wires of the three-wire set or unit, and the other terminals of said primaries being connected together and to a special neutral conductor; the secondaries of said three transformers being connected in a star 70 connection without any neutral conductor; a fourth and a fifth transformer, the primaries thereof being connected to said independent signaling circuits respectively; the secondary of the fourth transformer having its end terminals connected respectively to two of the secondary terminals of the first three transformers, and the secondary of the fifth transformer having one terminal connected to the central point of the secondary of the 75 fourth transformer and its other terminal connected to the secondary of the remaining one of the first three transformers; the three neutral wires from the three unit sets being conducted to a fourth transformer set arranged in the same manner in every particular as the transformer sets for the individual units, and also connected with two independent signaling circuits; whereby 80 nine individual wire conductors function first in groups of three, each group of three serving two circuits; and then the three groups of three function by means of their neutral wires as units forming an additional triplet set, and serve two additional signaling 85 circuits.

In testimony whereof I have signed this specification.

CAMILLE LOUIS MARIE RAVUT.
